& Birch, LLP(57) **CLAIM**

The ornamental design for a diaphragm pump as shown and described.

DESCRIPTION**1.1** : Front**1.2** : Back**1.3** : Right**1.4** : Left**1.5** : Top**1.6** : Bottom**1.7** : Perspective**1.8** : Perspective

An article of the present design is a diaphragm pump which transports fluid by reciprocation of a rod with compressed air; each end of the rod has a diaphragm; the present article comprises a valve body with a spool for switching the compressed air, and the diaphragms housed within left and right casings respectively; the compressed air is supplied from an inlet of the valve body, and is discharged from an outlet; the fluid is sucked through a suction port of in-manifold, and is discharged through a discharge port of out-manifold.

The broken lines depict portions of a diaphragm pump that form no part of the claimed design.
